(57) **CLAIM**

The ornamental design for a photography stand, as shown and described.

DESCRIPTION

FIG. 1 is a front perspective view of a photography stand showing our new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of portion 9 in FIG. 1;

FIG. 10 is an enlarged view of portion 10 in FIG. 1; and,

FIG. 11 is an enlarged view of portion 11 in FIG. 1.

The evenly broken lines in the drawings illustrate portions of the photography stand that form no part of the claim.

1 Claim, 11 Drawing Sheets
